UNITED STATES PATENT OFFICE.

HENRY W. JOHNSON, OF NAUGATUCK, CONNECTICUT.

CANDELABRUM.

Application filed May 6, 1927. Serial No. 189,198.

The invention relates to a candelabrum, more especially to a lamp-bearing frame which is especially adapted for display purposes, for example, at the Christmas season, 5 as a window or table decoration or for window advertising purposes.

It has for its object a candelabrum which may be compactly assembled for shipping purposes and which may readily be set up 10 for use and provide an artistic effect.

To this end, the invention comprises a pair of hingedly connected frame members adapted to carry suitable lighting elements and provided with pivotal blocks or feet 15 whereby the member may be located in various positions and adapted to different sizes of supporting members, for example, window frames.

The nature of the invention, however, will 20 best be understood when described in connection with the accompanying drawings, in which:

Fig. 1 is a front elevation of the candelabrum in set up position, a portion of the 25 frame being broken away; while Fig. 2 is a plan view of the same in folded position as for shipment purposes.

Fig. 3 is an elevation of the candelabrum as applied in a more contracted form.

30 Fig. 4 illustrates the candelabrum applied to a window frame above the sill portion thereof; and Fig. 5 is an elevation illustrating the candelabrum suspended from a ceiling or the like.

35 Referring to the drawings, the novel candelabrum is shown as composed of two frame members 10 and 11 of the required and equal length and secured together at their inner ends by a suitable hinge member 13 so that the two members may be swung apart or together in accordance with the particular design of candelabrum desired. Each frame member, moreover, is designed to receive a conductor 14; and to this end may be provided longitudinally along its under face 40 with a groove 15 into which said conductor is laid, the groove of one of the members being further provided with an outlet opening 16 through which the conductor extends 45 for external connection to a suitable source of power (not shown) through the usual lamp cord and standard plug. Said groove 15, furthermore, is provided with additional outlets 20 disposed along a frame member 50 and terminating in corresponding lamp

sockets 21 for receiving an imitation candle member or miniature electric lamp 22, the various sockets being connected in series and preferably four sockets being supplied for each of the two frame members, so that the 60 standard 14-volt lamps may be utilized and connected through the said lamp cord and plug with the usual household supply. Of course, instead of an electric lamp supplied with external power, an ordinary wax candle 65 (not shown) could be substituted; but it is preferred to utilize the electric candles both for safety and convenience.

In order to prevent the candle-carrying frame hereinbefore described from collapsing, each frame member is provided at its lower extremity with a block or foot member 25; and the same is arranged to be pivotally secured thereto. For example, an inwardly directed kerf or slot 26 may be cut 70 into a block and the corresponding end of a frame member pivoted between the walls thereof as by a suitable pin or shaft 27 driven therethrough and held in the said walls. By this expedient, the frame members 75 composing the candelabrum may be supported in various positions, for example, as indicated in Fig. 1 with the frame members 10 and 11 substantially at an angle of 90° to each other and at an angle of 45° to a supporting table or the like 30. Or, the members may be closed in as shown in Fig. 3 with the blocks abutting to provide a more contracted form of candelabrum and in which the candle members will be projected 80 from the frame pieces at an angle, whereas in the former embodiment they stand substantially vertical. The blocks or feet members 25 are further adapted to prevent undue separation or collapse of the candelabrum 85 through engagement of an end thereof with a suitable abutment 31, for example, as the side frames 32 of a window. Moreover, by swinging a block about its pivot point 27, different widths between abutments may be 90 accommodated.

If it be desired to positively insure the position of the candelabrum under conditions where abutments are not available for both the end and bottom of a block, for example, when locating the candelabrum in a window frame above the sill thereof, and as indicated in Fig. 4 of the drawings, a block 105 may be provided with an opening 33 drilled therethrough and through which may be in- 110

serted a screw 34 for attaching firmly the said block to the corresponding window frame. Similarly, a candelabrum may be attached to a ceiling or other support wherein the candelabrum is placed in an inverted or inclined position, as shown in Fig. 5 of the drawings. Various other arrangements, of course, will suggest themselves, and I do not wish to be restricted to the particular ones indicated.

When it is desired to collapse the candelabrum as, for example, for shipping purposes, this may conveniently be effected to provide a compact package thereof by turning outwardly the said blocks 25 over the corresponding frame members 10 and 11 upon which they are folded and then bringing together the said frame members as well as removing the lamps—a folded candelabrum being shown in Fig. 2 of the drawings.

By the foregoing expedient, a simple and effective candelabrum is provided and which, through the swingable blocks attached at the lower ends of the frame members composing the candelabrum, allows of the latter being mounted or secured in various positions, thus affording a great variety in mountings and designs in the lighting effects.

I claim:

1. A candelabrum, comprising two equal length frame pieces hingedly united at their upper ends, and having a longitudinal groove along the undersurface for a conductor and outlets therefrom to the upper surface, lamp sockets at said outlets, connected with the conductor, and adapted to receive lamps to be illuminated by current supplied through the said conductor, and supporting blocks pivotally secured to the respective opposite ends of the said frame pieces whereby the candelabrum may be supported in various positions.

2. A candelabrum device for displaying electric lamps in windows, comprising two equal length and hingedly united lamp supporting members, lamp retaining means carried thereby, end pieces hingedly secured to the respective opposite ends of said lamp supporting member and adapted for engagement with the sides of a window frame to support therein and spread the said lamp supporting members apart at an angle conforming to the width of the window frame.

In testimony whereof I affix my signature.

HENRY W. JOHNSON.
